Filed Oct. 14, 1969, Ser. No. 19,551

Term of patent 14 years

Int. Cl. D23—01
U.S. Cl. D23—45

FIG. 1 is a side elevational view of a corrugated tube showing my new design;

FIG. 2 is an elevational view taken from the left end thereof.

The characteristic feature of our design resides in the hollow frustoconical end section joined at its smaller diameter to a hollow cylindrical section with an axial length approximately two-thirds that of the frustoconical end section and a diameter the same as the largest diameter of the frustoconical end section, as shown in FIG. 1.

We claim:

The ornamental design for a corrugated tube, as shown and described.
